UNITED STATES PATENT OFFICE.

JOHN HOUF, OF SCHENECTADY, NEW YORK.

SAW-SETTING MACHINE.

SPECIFICATION forming part of Letters Patent No. 693,970, dated February 25, 1902

Application filed March 11, 1899. Renewed January 20, 1902. Serial No. 90,465. (No model.)

To all whom it may concern:

Be it known that I, JOHN HOUF, a citizen of the United States, residing at Schenectady, in the county of Schenectady and State of 5 New York, have invented new and useful Improvements in Saw-Setting Machines, of which the following is a specification.

My invention relates to machines for setting teeth of saws of the kind known as "band-saws;" and it consists of the novel combinations of novel parts and devices hereinafter described, and set forth in the claims.

The objects of my invention are to provide in a saw-setting machine certain combinations of devices and parts whereby certain operating devices in the machine may at will be adjusted so that saws having blades of different widths and of different thicknesses and having teeth of differing degrees or sizes as 10 to fineness and coarseness may have their teeth in pairs having opposite inclines rapidly set in true lines of similar inclinations and the blade be automatically moved the distance of two teeth at each movement for 15 carrying a pair of adjoining teeth to opposite and between a pair of oppositely inclined faces of anvils and a pair of set-hammers preparatory to their receiving their set in opposite directions of inclines.

Other objects and advantages of the invention will be fully understood from the following description and claims when taken in connection with the annexed drawings, in which—

Figure 1 is a horizontal view of a saw-setting machine embodying the improvements in my invention. Fig. 2 is a horizontal section taken at line 1 in Fig. 3. Fig. 3 is a side view of the same. Fig. 4 is a view of the 40 same from its front side, and Fig. 5 is a view from its rear side.

Similar letters of reference refer to similar parts throughout the several views.

In the drawings, A is a suitable frame made, 45 preferably, with a standard form comprising limbs a a, integral with base A', which is perforated at suitable points for receiving bolts or screws for securing it to a suitable table.

B B' are saw-clamping blocks secured on 50 the upper ends of limbs a a of the frame by suitable bolts or screws A² A³. One of these blocks, as B, Figs. 1, 3, and 4, is stationary,

while the other, as B', is movable and adjustable outwardly from block B or inwardly toward said block, as may be suitable for increasing or lessening the width of the saw-receiving groove b between said blocks for adapting said groove to nicely receive the blade of the saw and allow it to be moved endwise and yet hold it from having lateral play 60 between said blocks. The adjustable block B' has its screw-receiving holes b', Fig. 1, made slightly oblong, as shown by dotted lines in Fig. 1, the screw being removed. B² B³ are adjusting-screws passing freely 65 through perforations provided in the upper ends of brackets B³ B³ and screwing in said block B', while check-nuts b² b³, working on said screws at near its finger-turning head b³, may be set against the outer sides of brackets B³ B³ for preventing adjustable block B' 70 moving inward toward the stationary block B. Reacting springs B⁴ B⁴, arranged between the adjustable block B' and brackets B³ B³, operate to crowd said adjustable block 75 toward the stationary block, so that the saw-blade between said two blocks will be elastically clamped and allowed to be moved lengthwise between said blocks.

C C are anvils, which are securely fixed on 80 blocks B B' or made integral with them and have their face sides c c inclined outwardly from the sides of the blocks forming the groove b, between which the teeth of the saws are to move. These anvils C C are located 85 staggering in relation to each other, with their near corners adjacent and their face sides having like angles of inclination in opposite directions.

D is an adjustable gage-bar arranged in the 90 groove b and extending through the entire length of said groove and outwardly in opposite directions past the outer ends of the saw-clamping blocks for service as an extended support to a saw from its back when seated 95 thereon. This adjustable gage-bar D has its outer ends connected with suitable gage-supports D' D', which are loosely mounted on the outer ends of adjusting-screws D² D², which may freely revolve in the perforations provided for them in said supports while they work through screw-threaded perforations in brackets D³ D³, connected with the limbs of 100 said frame A. A mash-nut d² on each screw

operates to hold them fixed when set, and a finger-pin ∂^3 serves as a convenient means for revolving said screws, by means of which the gage-bar may be raised or lowered in the 5 groove between blocks B B' to such a depth as may be found to be suitable for holding the blade of the saw with the base-line of the teeth of the same on a line with the plane of the base of the anvils or top surface of the blocks, and 10 in all cases this gage-bar serves as an adjustable bottom of the groove.

E E are set-hammers arranged above the clamping-blocks B B' and having their setting-faces e e, Figs. 1 and 5, inclined for correspondence with the inclines of faces c c of the anvils they may be opposite. These set-hammers may be operated by means of any suitable mechanism adapted to impart to them a quick forward movement with suitable 15 percussion for carrying the points of the teeth against the inclined faces of said anvils simultaneously, that oppositely-inclined sets may be given to two adjoining teeth at the same time, when suitable other mechanism 20 may be provided will operate to carry those set-hammers back from the set teeth preparatory to striking another pair of adjoining teeth. These hammers are adjustable both in a horizontal and vertical direction and set in situation adjusted to, in relation to the inclined 25 faces of said anvils, for adapting said hammers for operating with teeth of different sizes, as may be found in different saws.

F F, Figs. 1, 2, 3, 4, and 5, are levers, on 30 the upper ends of which the set-hammers E E are mounted and are adjustably secured by means of pivot f, integral with each said levers, and pivot-hole e' through the head of each hammer, and set-screw E', screwing 35 through a screw-threaded perforation in the head and against the pivot f. These levers F F, which may be made with any suitable form, cross each other at about the middle of their length and are pivoted on each other by 40 pivot F', which is supported from the limbs a a of the frame. The lower ends of these pivoted cross-levers are each provided with an inwardly-projected toe f', and the upper arm of each lever is provided with eye f², located 45 at a point about midway between the pivot F' and the head of the set-hammer E the lever carries. The toes f' f' on the lower ends of the pivoted cross-levers F F are projected inwardly toward each other, as shown 50 in Fig. 4, and one of said toes has its forward end made with incline f³, which is preferably of convex form, running from the lower edge of the toe up to the top line f⁴ of the same, while the other toe has its forward end made 55 with incline f⁵, preferably of convex form and running from its upper side down to the lower straight line f⁶, as shown in Fig. 4.

G G are cross-bars secured in the eyes f² of each lever. G' G' are coiled springs which 60 are each connected by their opposite ends with said cross-bars G G and preferably by means of devices by which the tension of the

said springs may be increased or lessened at will for increasing the force of the blow of the hammers or lessening the same, as the 70 stiffness of the teeth of the saws may require. One end of each of these springs is secured to the outer end of one of these cross-bars G by being hooked on the same, while the opposite ends are respectively secured to the outer 75 ends of the opposite cross-bar by means of adjusting-screws g, passing through said cross-bar at each end and screwing in head-pieces g', secured to an end of each said spring and having on each a mash or set nut g². 80 When these adjusting-screws are turned in proper direction, the tension of these springs will be increased, and be lessened when turned in an opposite direction.

H H are dual wipers mounted on revolving 85 shaft H', which shaft is supported in suitable bearings provided in the frame A and is arranged midway between said toes f' f' of the crossed levers and in direction transverse to the direction of movement of same. These 90 dual wipers are preferably integral and are shown to have their faces h h made on curves of a true circle, with their respective points h' h' of termination of throw on line with the center of rotation of the shaft on which said 95 wipers are mounted, which shaft H' is relatively eccentric to the curved faces h h of the former, as shown in Fig. 4. When the toes f' f' of each lever F are in contact with the point of least throw of said wipers, the lower 100 and upper ends of said levers are at the full limit of their throw toward each other, and when said wipers are revolved in proper direction by said shaft H' the faces of said 105 wipers are progressively moved in contact with said toes f', so as to gradually spread both their upper and lower ends apart until the greatest throw of said wipers, as at points h' h', has been reached, when toes f' f' of said 110 levers will run off from the curved faces h of said wipers and said levers under the impulse of springs G G be suddenly operated 115 with such a sufficient force as may be given them under their previous adjustment and throw both set-hammers E E against the two 120 teeth opposite the respective anvils C C and between them and said set-hammers. The 125 shaft H', on which these dual wipers are mounted, may be revolved by hand or by any suitable power, as may be preferred. The drawings, Fig. 3, show both a band-wheel H² and handle H³, by either of which said shaft 130 may be revolved.

I is a pawl pivoted by an adjustable pivot i on lever J. This adjustable pivot is secured to said lever by means of clamping-bolt i', (indicated by dotted lines in Fig. 1,) secured in place in the downwardly and inwardly inclined slot-form perforation j in the upper end of said lever, clamping-collar i², and 135 clamping-nut i³. (Shown in said Fig. 1 in connection with Fig. 3.) Lever J is pivoted to bracket J', supported from the frame A, and has its lower end made with any pre-

ferred form of toe j' , through which cam L, mounted on shaft H', on which the dual wipers H H are mounted and in relation to which the said cam is timed in its movement 5 of throw, may impart motion to said lever for throwing the upper end of lever J and the pawl I, carried by the latter, forward while in engagement with the teeth of the saw as soon as the set-hammers have delivered their blows 10 on the teeth opposite, and thereby move the saw forward to the distance of two teeth, when the limit of the throw of the cam L will be reached, and the forward movement of the pawl I will cease and spring k, between pivot-pin J² of said lever and the toe end of the same, operates suddenly to move said lever so as to carry the saw-moving pawl back from engagement with the teeth it pushed against to the distance of the next two teeth back for 15 engagement with the saw at such point preparatory to being moved forward after the set-hammers have delivered their next blows to the teeth of the saw opposite.

L, Figs. 2, 3, and 5, shows my preferred 20 form of cam for operating lever J. This cam is shown to be mounted on shaft H', on which the dual wipers H H are mounted, and revolves with it. The cam L is so arranged in relation to the dual cams that the highest 25 point of cam-surface l on cam L will pass off from bearing on the toe j' of said lever J at the same time the highest points of cam-surface in dual wipers H H are carried past, bearing against the toes f' f' of levers F F, so that 30 both the crossed levers may be acted on by their operating-springs only an instant before the said pawl-carrying lever is acted on by its spring.

M is an adjusting-screw located between 35 the lower arm of lever J and a screw-receiving piece m, connected with the frame, which piece is perforated and screw-threaded to receive the screw-threaded stem of said adjusting-screw, which is provided with a suitable 40 finger-wheel m' and the gaging-head m², Fig. 3. When this adjusting-screw is revolved in one direction, its gaging-head m² will be carried outward for gaging the distance of back throw of the pawl I, carried by lever J. 45 50 When said screw is set in to its whole distance allowed, then the length of throw of pawl I will be greatest, and when set out it will be lessened. By means of this adjusting-screw and the adjustable pivot i in the slot-form pivot-hole j and pawl I on said pivot the throw of the said pawl can be nicely adjusted for operating with the teeth of fine or coarse toothed saws for moving such saws the 55 length of two teeth at each forward movement 60 of said lever J.

This machine may be made with any preferred size for operating with band-saws varying in width of blade from one-half to one inch, or from one inch to three inches, or from 65 two inches to five or more inches in width, as may be found in use in lumber-manufacturing mills, and may be operated by steam, wa-

ter, or electric power or by hand, as may be preferred.

Having described my invention, what I 70 claim, and desire to secure by Letters Patent, is--

1. In a saw-setting machine, the combination with a suitable frame, saw-clamping blocks B B', anvils C C provided with similar 75 inclined faces c and arranged staggering on said blocks, of crossed levers F F pivoted together at points midway between their opposite ends and provided at their lower ends with toes f' f' of form described and projected 80 inwardly toward each other, set-hammers E E adapted to be vertically adjusted and fixedly secured on the upper ends of said levers, dual wipers H H of form described mounted on a revolving shaft which is arranged transverse to the lines of movement of the lower arms of said levers, and the adjustable contracting springs G' G' connecting the upper arms of said levers and operating to simultaneously carry said set-hammers with sudden 85 blows against the saw-teeth opposite said anvils, substantially as and for the purposes set forth.

2. In a saw-setting machine, the combination with saw-clamping blocks B B' having a 90 saw-receiving groove between, anvils C C having like inclined faces c and located staggering in relation to each other on said blocks and with their adjoining corners at said groove, crossed levers F F pivoted together 95 at about their middle of length and having at their lower ends toes f' f' described, and set-hammers E E adjustably secured on the upper ends of said crossed levers and having ends e of inclination of face corresponding 100 with the inclines of the faces of said anvils, of revolving dual wipers H H of form described and revolving in contact with the toes of said levers, cross-bars G G which are respectively 105 transversely connected to the upper end portions of said levers, adjustable contracting springs G' G' connecting said cross-bars and adjusting-screw mechanism described connecting an end of each of said springs with an end of each of said cross-bars, substantially 110 115 as and for the purposes set forth.

3. In a saw-setting machine, the combination with a suitable frame, stationary clamping-block B, adjustable clamping-block B', adapted to be moved horizontally toward and 120 from said stationary clamping-block and anvils C C described, integral with said blocks and relatively staggering and having like inclinations of faces c, of brackets B B³ supported from said frame, springs B⁴ B⁴ between 125 said adjustable block and the said brackets, adjusting-screws B² B² and check-nuts b² b² for operation, substantially as and for the purposes set forth.

4. In a saw-setting machine, the combination with the crossed levers F F, pivot-pin F' and set-hammers E E carried by the upper ends of said levers and adapted to be adjusted at will horizontally or vertically, of revolv-

ing dual cams H H operating with the lower ends of said levers, of cross-bars G G carried by the upper arms of said levers, percussion-springs G' G' between said cross-bars, and 5 mechanism for increasing or lessening, at will the tension of said springs, substantially as and for the purposes set forth.

5. In a saw-setting machine, the combination with a suitable frame, stationary clamp-10 ing-block B, adjustable clamping-block B' and the vertically-adjustable gage-bar D between the said clamping-blocks and forming a support for a saw, from its back edge, and having its end portions extended outwardly 15 past the respective ends of said clamping-blocks, and suitably supported, of lever J having with its lower end the toe j' and its upper end the inclined slot j, adjustable pivot i adapted to be variously located in the said 20 slotted upper end of the lever, pawl l loosely working on said pivot with its free end riding on the outer end portion of one of said clamping-blocks and vertically over the said vertically-adjustable gage-bar, revolving

cam L having an inclined side face revolving in contact with the toe of the lever J, and the reacting spring k between the pivot of said lever and the rearward side of the lower arm of the same substantially as and for the purposes set forth. 25

6. In a saw-setting machine, the combination with the pivoted crossed levers F F, set-hammers E E, carried by said levers, of the cross-bars G G arranged transversely to said levers, of percussion-springs G' G' having 35 each an end secured to one of said cross-bars, of headpieces g' g' provided with screw-threaded holes and holding with the opposite ends of said springs, adjusting-screws g g working each through a perforation provided 40 in the opposite cross-bars and screwing into said headpieces and mash-nuts g² on said screws, substantially as and for the purposes set forth. 30
